BELT DRIVEN ROLLER MILL WITH ADJUST-
ABLY AND YIELDABLY MOUNTED ROLLERWilliam P. Blake, Fairmont, Okla., assignor to
K & B Manufacturing Co., Fairmont, Okla.

Application June 25, 1946, Serial No. 679,202

2 Claims. (Cl. 241—230)

1

The present invention relates to improvements in grinding machinery and more particularly to a machine for grinding light materials such as grain, paint materials, etc.

One of the objects thereof is to provide a simple, efficient and inexpensive grinding machine possessing the characteristics of sturdiness, dependability, ease of automatic operation, proper equilibrium of all movable parts and accuracy of the timing of the various movable parts that accomplish not only grinding of the material but regulator feeding thereof for grinding purposes.

A still further object thereof is to provide, in a grinding machine, improved means for applying spring tension upon the grinding rollers when they have been brought together to coact for material grinding purposes, so they may yield retractingly as conditions in the accumulation of material upon the rollers or between them necessitates.

Another object thereof is to provide, in a device of the kind described, improved means for loosening the material which may have been lumped together at the point of discharge upon the grinding rollers just prior to a grinding operation performed thereupon, so that the material may not become clogged up or be supplied to the rollers in too dense a mass.

A further object thereof is to provide, in a device of the kind described, improved means for imparting rotation to the grinding rollers in a simplified yet effective manner as they are moved towards or from each other intermittently.

A further object thereof is to provide, in a device of the kind described, improved means for tensioning or stretching the driving belt of the grinding machine which is responsible for imparting rotation to the grinding wheels in opposing directions so they may feed down into a discharge hopper the material being ground and having been ground.

A still further object of this invention is to provide driving mechanism for the grinding rollers so arranged and functioning therein, that they not only impart rotation to the rollers but also time and control the operation of the means for advancing and retracting the grinding rollers and operation of an agitator in the upper hopper for loosening the material in the latter that is to be fed upon the grinding rollers.

With the above and other objects in view, my invention consists in the arrangement, combination and details of construction disclosed in the drawings and specification, and then more particularly pointed out in the appended claims.

2

In the drawings, wherein similar reference characters designate similar parts throughout the respective views,

Figure 1 is a front end elevation of my invention,

Figure 2 is a side elevation of my invention,

Figure 3 is another and opposite side elevation thereof.

Figure 4 is a section taken on line 4—4 of Figure 1 looking in the direction of the arrows,

Figure 5 is a cross section taken on line 5—5 of Figure 2, looking in the direction of the arrows,

Figure 6 is a plan view of the inner face of one of the sides of the upper hopper showing manually controlled means for controlling feed of material through the chute of this hopper,

Figure 7 is a fragmentary section taken on line 7—7 of Figure 6, looking in the direction of the arrows, and

Figure 8 is a section taken on line 8—8 of Figure 6 looking in the direction of the arrows.

Referring to the drawings, which are merely illustrative of my invention, the various parts of my invention are disclosed. The device or machine consists of vertically separated hoppers, a frame supporting the hoppers, means for driving the grinding rollers arranged in the lower hopper, means for intermittently bringing the rollers into and out of engagement for coactive grinding operation, and means for agitating intermittently the material in the upper hopper that is to be supplied into the mouth of the lower hopper.

The framework of the machine will first be described. This consists of the oppositely arranged base sills, the vertical sides 10, 11 of which are secured to opposite pairs of upright sills, while their horizontal sides 10a, 11a rest upon the flooring. Four upright angle iron sills are provided at the four corners of the base sills, which are designated 12, 13 at one end of the machine, and 12a, 13a at the other end thereof. The upper ends of the upright sills are designated 14. Resting upon these ends 14 of the upright sills are four more extension upright sills, also angle iron members, designated in accordance with their sides. The two right angular sides of one extension upright sill are designated 17, 17a. The other extension upright sill, at the same side of the machine have their sides designated 18, 18a. Similarly designated angle iron extension sills are located at the other side of the machine. It will be seen that the two right

50 55

angular sides of the extension upright sills rest upon the right angular sides of the main upright sills but with their webs at right angles to the webs of the main upright sills. These two pairs of upright sills of the frame may be secured to each other rigidly in any desirable manner. A rigid cross bar 19 spans the lower upright sills at each side of the machine being secured to such upright sills at its opposite ends. This effectively braces the lower framework.

The upper ends of the extension upright sills are designated 20. Attached to these ends 20 of the mentioned sills are angle iron horizontal sills 21 arranged at opposite sides of the machine. The upper hopper is secured in depending relation to these sills 21. Cross bars 15 are arranged at opposite ends of the machine, being secured at opposite ends to the lower parts of the extension upright sills to brace the same. At right angles to the last named cross bars 15, and secured thereupon so as to span the distance between the extension upright sills, at each side of the machine, are angle iron bracing bars 16 and 17 respectively. The horizontal sills 21 are cross connected at their opposite ends and are located at opposite ends of the machine operatively by the sills 23, 24, two in number.

The upper hopper of the frame has parallel side walls 27, 28 and oppositely and downwardly inclining and converging end walls 25, 26 which if produced to their lowermost ends would come to a point. The upper ends of the four walls of this hopper are operatively secured to the sills 20, 21 and to the two cross sills 23, 24 in a manner to depend therefrom so the lower chute part of the upper hopper is directly over the mouth of the lower hopper about to be described.

The lower part of the inclined wall 26 of the upper hopper has an elongated marginal slot 30 formed therein, or is preferably spaced above the adjacent lowermost end of the inclined wall 25 of the same hopper. This provides a discharge opening for the material to come out of the upper hopper when this opening is uncovered by a gate now to be described. Along a medial vertical line of this side 26 of the upper hopper, as seen in Figure 6, a pair of oppositely arranged keepers 35, 36 are secured thereupon in which is slidably guided a thrust bar 34 at its opposite ends. The lower end of the thrust bar 34, just after leaving keeper 35 is attached to a cross bar forming the gate between the ends of the latter. Keepers are also provided at opposite ends along the lower margin of this side wall 26 of the hopper, consisting of inner base portions 33 secured to this wall and offset raised portions 32 into which the gate bar 31 slidably projects and is adapted to be seated in order to close the opening 30 in the lower chute of the hopper.

Manually controlled means is furnished for operating the thrust bar 34. It consists of a hand lever 36 pivoted at its inner end at 37 to a cleat 39 operatively secured to the outer side of wall 26 of the hopper. Between its ends this operating handle lever 36 is pivoted at 35 to the adjacent end of the thrust bar 34. The handle portion of this operating lever 36 is designated 38.

The lower end of the upper hopper, where its chute is located, may be rigidly or otherwise secured in position upon the frame in any desirable manner. I seat the lowermost end of wall 25 thereof upon an angle iron member 40 supported rigidly upon pieces 47 secured upon the frame. The lowermost end of wall 26 is supported upon a strut 41 which is also secured to the pieces 47.

The pieces 47 are arranged at the ends of the machine so that the bottom of the chute with its opening 30 extends transversely of the machine directly over the grinding rolls which will now be described.

The lower hopper is open at its top or mouth end. It is a box-shaped body having parallel side walls 44, 45, and end walls 42, 43. Inside of this hopper is a separate chute, which chute has a delivery end opening out of the side, not end of the machine, as shown in Figure 1. This chute consists of oppositely inclining walls 53, 54, opposite the inner faces of the walls 42 of the lower hopper, a vertical front wall 48b at one side of the machine and a downwardly and forwardly inclining bottom wall 48a which has an extension 49 projecting beyond the side of the machine and continuing the inclination of the bottom wall 48a. Scoop-shaped side walls 50 delimit the extension bottom 59. The channel of this discharge scoop is designated 51. Corner bracing angle bars 46 are secured to the lower hopper. The interior of the chute is designated 52.

At the top of the lower hopper the oppositely and horizontally extending shelves 47a mounted thereupon, as shown in Figure 4, provide the mouth or passageway 55 of the lower hopper at its upper end for material to enter which is discharged from the upper hopper. A pair of oppositely arranged shafts 56 and 57 have their ends journaled in opposite side walls of the lower hopper. The shaft 56 is pulley driven, and fixedly mounted. The other shaft 57 is movably mounted and shiftable laterally of shaft 56 but in horizontal elongated slots 61, 61a formed upon walls 44, 45 of the lower hopper proper, and also project endwise into slide blocks 85, 85a hereinafter more fully described. Two preferably hollow grinding rollers 58, 59 are made fast upon the shafts 56, 57 respectively. The end walls of these rollers are closed as at 58a. The slit between their working surfaces, which are fluted as at 60, is designated 48, when the rollers are separated for this purpose.

A pair of frames are arranged at the opposite sides of the frame being attached operatively to the sides 44, 45 thereof. As seen from Figure 1, endwise, these frames have channelled portions 86 in which the slide blocks 85, 85a are received and slidably held and guided in movement. Made fast upon the projecting end of shaft 57 which extends out from slide block 85a, is a disc 98c. Made fast upon the projecting end of shaft 56, in line with disc 98c is a disc 98a.

A large driving pulley 63 is made fast upon the outer end of the shaft 56 and spaced away from the side of the machine. An endless belt is made use of for rotating a pair of pulleys mounted on shafts 56, 57, and another pulley is located on a rocker arm soon to be described. The pulleys 64 and 65 are held by collars 67 secured around shafts 56, 57, respectively. These collars are secured fast thereupon by means of set screws or the like 68. The collar which confines the third pulley 66 is held around a pin 69 secured at the upper end of a rocker arm or lever 71, the collar being held against displacement from this pin 69 by cotter pin 68 which removably engages this pin. The rocker arm 74 is mounted oscillatingly, just below its uppermost end, eccentrically, upon a pin 72 secured to brace bar 19, and is confined on the pin by means of a collar 73 which embraces this pin 72. A cotter pin 74 removably engages the

pin 72 and holds the hub 73 on the pin nondisplacedly.

The lower end of the rocker arm 71 has attached thereto the hook end 75 of a contractile spring 76, the opposite end 77 of which is hooked onto the eye 78 of a bolt 79 which has its threaded shank 80 screwed into the lug 81 of a bracket 82 rigidly secured by fasteners 83 to upright sill 13a.

The belt is trained around pulley 65 fast upon shaft 57 as at 85m. It is trained around pulley 66 loose on pin 69 as at 89. It is bowed as at 86c and made to be trained around and over the lower dead center of pulley 64 on shaft 56 as at 87m. It has a straight stretch 84 which runs from the lower dead centers of the pulleys 65 and 66 respectively. It is proposed to so tension the contractile spring 76 by adjusting the screw bolt 79 in bracket 82 properly for this purpose, that the lower rocker arm end will be held at a bias shown in Figure 2. In this position of the rocker arm 71, its upper end is shifted to the left of the frame, which moves the belt along with it, and causes pulley 65, made fast on the movable shaft 57, to move to the inner ends of the registering slots 61, 62, and 61a, 63 at the opposite sides of the frame. This positions the grinding rollers 58, 59 (Fig. 4) in touching or nearly touching relation, according as to how the machine is set.

Means is provided for advancing and retracting the roller 59 with relation to the roller 58. This is illustrated in Figure 3. Here it is seen that the disc 98a on shaft 56 carries a wrist pin 100. A crank has one end pivoted upon wrist pin 100, this crank being denoted at 99. The other end of this crank 99 is pivoted at 98 to the lower end of a link arm 101, which is vertically disposed. The upper end of this link arm 101 is made fast upon a pintle 102 that extends into the chute of the upper hopper and has its ends mounted in the walls 27, 28 of this hopper. Inside of the chute extending transversely thereof, is a blade carried by the pintle 102.

It will also be seen from the various figures that set screws 90 are employed which have inner screw threaded portions or shanks 93 abutting the discs 98c on shaft 57. These set screws 90 are screwed into lugs 92 formed upon the frames 86. Lock nuts 94 are threaded upon the screw bolts 90 so as to abut opposite sides of each lug 92. Oil cups 103 are operatively carried by the discs 98c. The discs do not rotate, but receive rotatably, the ends of shaft 57. In Figure 5 it is seen that tubes 95, 95a are respectively secured at one end to discs 98d disposed upon the opposite ends of shaft 56 and attached to frames 87, 86b respectively. Located confinedly in these tubes at their inner ends are contractile springs 96, 97 respectively. The other ends of these springs project beyond the tubes and bear against the discs 98c at the opposite ends of the shaft 57.

The use and application of the present invention is as follows: The parts are normally set so as to place the two grinding rollers 58, 59 either in contacting relation or in such a nearly engaging disposition as to leave only the narrow slit 48 between them seen in Figure 5. This depends how the screw bolt 79 is adjusted in bracket 82, which determines how far the rocker arm 71 will be tilted to make its upper pulley carrying end tension the belt as well as make pulley 66 carried by this rocker arm move to the left to cause pulley 65 to move also to the left and carry shaft and roller 59 along with it. Of course in thus presetting the rollers regard is paid to permitting material from the upper hopper to be positioned

between the grinding surfaces 60 of these two grinding rollers.

This having been done, the pulley 63 is set in rotation. Material to be ground, such as paint or coarser material such as paint materials, is introduced into the upper hopper. The operator stands by to operate the hand lever 36 controlling the gate 31 which covers and uncovers the discharge port 30 in the bottom chute end of this upper hopper. It is seen that when the operator raises up on handle 38 of lever 36 the effect is to raise also the thrust bar 34 to which the gate 31 is attached, so this bar moves upwardly into its keepers 32 and uncovers the port 30. The material in this chute is now free to drop into the mouth 55 of the lower hopper upon the peripheries of the grinding rollers 58, 59 upon both at the same time.

As the pulley 63 is being rotated operatively, it sets the belt in motion. As the belt moves around the three pulleys 66, 64 and 65, it sets the same also in rotation. This is done as follows: The lower stretch 84 of this belt travels in the direction of the indicated arrows or to the right. In doing so it rotates the pulley 65 on shaft 57 counterclockwise, while the bowed portion 86c of the belt by means of portion 87n which engages the under side of pulley 64 on shaft 56 causes pulley 64 to rotate since this pulley is directly made fast on the shaft which carries the driving pulley 63. As the belt thus travels it also rotates the pulley 66 counterclockwise. Pulley 64, in rotating, turns clockwise in order to make the lower stretch 84 of the belt travel to the right. In this way all three pulleys rotate constantly.

During each rotation of the shaft 56, the wrist pin 100 is carried around with it in a cycle, which carries crank 99 around in a cycle also. As this crank thus moves around with shaft 56, it oscillates back and forth the link arm 101. This causes the blade 104 in the chute of the upper hopper to oscillate in unison with the link arm 101. As this blade is thus oscillated the material lying in the bottom of the upper hopper in its chute is agitated forcibly and put in a sufficiently loose condition to drop down by gravity freely out of discharge port 30 into the mouth 55 of the lower hopper, where the material falls upon and between the crushing sides of the rollers 58, 59.

As this roller 59 moves away from fixed rotating roller 58, the contractile springs 96 and 96a which are secured to the collars 98d expand automatically and thus tension with spring pressure the rollers. When the roller 60 approaches the roller 59, on the other hand, these springs are compressed and again the rollers are tensioned. It will also be noted that when the roller 59 moves away from roller 58, so that its shaft 57 moves towards the outer ends of the slots 61, 62 and 61a, 63 at opposite sides of the machine, the belt is carried along with it on pulley 65 made fast on this shaft 57. In doing so, the belt tilts the rocker arm 71 forwardly, and this moves the lower end of the rocker arm rearwardly against the tension of the contractile spring 76. Contrariwise, when the roller 59 is advancing towards the roller 58, rocker arm 71 recedes back to normal position under influence of the spring 76 which now may relax and cause this motion. It is thus seen that when the roller 59 advances towards roller 58 pressure springs 96, 96a are compressed, while spring 76 contracts, and when this roller 59 is retracted or moves away from roller 58 springs 96, 96a expand, while spring 76 expands. Equilibrium is thus maintained at all times necessary

for holding the rollers in true grinding position yieldably.

The spring tensioned rollers enable the material being crushed by the grinding action of the rollers 58, 59, to move the rollers apart according to the density of their moving mass. When these rollers open, the material is freshly deposited between the crushing rollers. After this mass has been crushed, the rollers when they separate widen the passage between themselves to freely permit the ground material to drop down into the inclining bottom of the chute in the lower hopper indicated at 48a. By gravity the ground mass is carried down the incline into the scoop 51 and discharged into a suitable receptacle.

I do not mean to confine myself to the exact details of construction herein disclosed save as covered by the appended claims.

What I desire to claim is:

1. In a device as described, a frame, a pair of oppositely arranged slide blocks guided therein, a shaft having its ends journalled in said slide blocks, a second shaft having its ends fixedly journalled in said frame, a driving pulley made fast on the latter shaft at one end, a rocker arm pivoted adjacent its upper end to said frame, a second pulley journalled at the upper end of the rocker arm, pulleys made fast on the shafts and in line with the rocker arm pulley, a belt trained around the second pulley, around the pulley on the shaft on the slide blocks and bowed into engagement with the under side of the remaining pulley; a spring having one end fixedly mounted on said frame, and the other connected to the lower end of said rocker arm for tilting said rocker arm to slide the slide blocks to positions in which the two shafts approach each other, and expansible means between the ends of the shafts for engaging said slide blocks and moving them in a counterdirection and for tilting said rocker arm in a counterdirection to tension said rocker arm spring.

2. In a device as described, a frame, a pair of oppositely arranged slide blocks guided therein, a

shaft having its ends journalled in said slide blocks, a second shaft having its ends fixedly journalled in said frame, a driving pulley made fast on the latter shaft at one end, rollers on said shafts, a rocker arm pivoted adjacent its upper end to said frame, a second pulley journalled at the upper end of the rocker arm, pulleys made fast on the shafts and in line with the rocker arm pulley, a belt trained around the second pulley, around the pulley of the shaft on the slide blocks and bowed into engagement with the under side of the remaining pulley, a spring having one end fixedly mounted on said frame, and the other connected to the lower end of said rocker arm for tilting said rocker arm to slide the slide blocks to positions in which the two shafts approach each other, and expansible means between the ends of the shafts for engaging said slide blocks and moving them in a counterdirection and for tilting said rocker arm in a counterdirection to tension said rocker arm spring.
